The ornamental design for a vehicle side mirror, as shown and described.

DESCRIPTION

FIG. 1 is a rear perspective view of a vehicle side mirror showing our new design;

FIG. 2 is a front perspective view thereof;

FIG. 3 is a rear elevational view thereof;

FIG. 4 is a front elevational view thereof;

FIG. 5 is a side elevational view thereof;

FIG. 6 is a top elevational view thereof;

FIG. 7 is a bottom elevational view thereof;

FIG. 8 is a rear perspective view of a right-hand version thereof;

FIG. 9 is a front perspective view of a right-hand version thereof;

FIG. 10 is a rear elevational view of a right-hand version thereof;

FIG. 11 is a front elevational view of a right-hand version thereof;

FIG. 12 is a side elevational view of a right-hand version thereof;

FIG. 13 is a top elevational view of a right-hand version thereof; and,
